CLAIM

The ornamental design for a combined cosmetic sharpener and cap, as shown and described.

DESCRIPTION

FIG. 1 is a front, side and bottom perspective view showing our new design with the cap in its open position;

FIG. 2 is a bottom plan view thereof;

FIG. 3 is a front elevational view thereof;

FIG. 4 is a top plan view thereof;

FIG. 5 is a side elevational view thereof, the side opposite being a mirror image of the side shown;

FIG. 6 is a rear elevational view thereof;

FIG. 7 is a front, side and bottom perspective view showing our new design with the cap in its closed position;

FIG. 8 is a bottom plan view thereof;

FIG. 9 is a front elevational view thereof;

FIG. 10 is a top plan view thereof;

FIG. 11 is a side elevational view thereof, the side opposite being a mirror image of the side shown; and,

FIG. 12 is a rear elevational view thereof FIG. 7.
